2,045,512

ELECTRIC INCANDESCENT LAMP

Jan Bergmans, Eindhoven, Netherlands, assignor
to General Electric Company, a corporation of
New York

Application June 18, 1934, Serial No. 731,148
In the Netherlands June 24, 1933

5 Claims. (Cl. 176—34)

My invention relates to electric incandescent lamps and more particularly to lamps for use in vehicle headlamps.

It is desirable that the light beam projected upon the road from vehicle headlamps be spread laterally in such a manner that the sides of the road are properly illuminated. It is also desirable that there be no light and dark spots in the beam, that is, that a cross section of the beam be substantially uniformly lighted.

According to my invention a light beam of the type described above is obtained by providing the surface of the bulb with suitably disposed flutes. The flutes are disposed in such a manner as to provide a laterally elongated light beam when the lamp is used with a reflector without a configurated lens. The flutes are also arranged so as to make the bulb easy to manufacture.

Further features and advantages of my invention will appear from the following description of a species thereof.

In the drawing Fig. 1 is a somewhat diagrammatic perspective view of a lamp comprising my invention; Fig. 2 is a front view of the bulb; Fig. 3 is a partial plan view of the bulb with a partial section therein at the horizontal plane through the bulb axis; and Fig. 4 is a diagrammatic representation of beams produced by the lamps made according to my invention.

Referring to Fig. 1, the lamp comprises a base 10 and a bulb 11 having a pair of filaments 12, 13 sealed therein and located substantially in the longitudinal axis 14 of the lamp. The filament 12 is disposed at the focus of the usual paraboloidal reflector of a headlamp to provide the main driving beam. An internal reflector 15 is located below the forwardly disposed filament 13 to direct the rays from said filament against the upper half of the paraboloidal reflector of the headlamp to provide a depressed beam.

The upper surface of the bulb 11 is provided with flutes 16 which are located in vertical planes 17 which have a common line of intersection 18 which is perpendicular to the horizontal plane 19. The line 18 is tangent to the tip 20 of the bulb 11 through which the longitudinal axis 14 passes. The flutes 16 extend on each side of the bulb to planes 21 which form angles preferably of from 95 to 105 degrees with the vertical plane 22 which also intersects the line 18. That is, the angles 23 between the planes 21 and the horizontal plane 19 are of the magnitude of from 5 to 15 degrees. As many flutes are provided as the manufacture of the bulb permits; for ex-

ample, six per cm. of bulb periphery, measured at the horizontal plane.

The lower part of the bulb is also preferably provided with fluted portions 24, 25 (Fig. 2). The flutes in the portion 24 are located in planes which have a common line of intersection 20—26 which is tangent to the bulb 11 at the point 20 and makes an angle 27 of from 5 to 15 degrees with the vertical plane 22. The flutes in portion 25 are located in planes which have a common line of intersection 20—28 which is also tangent to the bulb 11 at 20 and makes an angle 29 of from 5 to 15 degrees with the vertical plane 22.

A smooth strip 30 is preferably left on the bulb between the upper and lower fluted portions for purposes of adjusting the position of the internal reflector 15 and the filaments with respect to the bulb.

The full line pattern in Fig. 4 illustrates a cross-section of a "dumb-bell" shaped driving beam obtained when the filament 12 is energized. The dotted lines indicate a beam pattern which might be termed ideal, the ends thereof being depressed below those of the full line pattern.

What I claim as new and desire to secure by Letters Patent in the United States is:

1. An electric incandescent lamp comprising a bulb having a plurality of flutes on the surface thereof for spreading the light transmitted therethrough, said flutes being located in planes having a common line of intersection which is tangent to the bulb.

2. An electric incandescent lamp comprising a bulb having a plurality of flutes on the upper portion of the surface thereof located in vertical planes having a common line of intersection which is tangent to the tip of the bulb and perpendicular to the longitudinal axis thereof.

3. An electric incandescent lamp comprising a bulb having a plurality of flutes on the upper portion of the surface thereof located in vertical planes having a common line of intersection which is tangent to the tip of the bulb and perpendicular to the longitudinal axis thereof, and a plurality of flutes on the lower portion of the surface of said bulb when horizontally placed, the flutes on each side of said lower surface being located in planes having a common line of intersection which is tangent to the said tip of said bulb and forms an angle with the vertical plane through the bulb axis.

4. An electric incandescent lamp comprising a bulb having a pair of filaments disposed substantially in the longitudinal axis thereof and a concave reflector disposed below one of said fila-

ments, said bulb when horizontally placed having a plurality of flutes on the upper portion of the surface thereof located in vertical planes having a common line of intersection which is tangent to the tip of the bulb and perpendicular to the longitudinal axis thereof.

5. An electric incandescent lamp comprising a bulb having a pair of filaments disposed substantially in the longitudinal axis thereof and a 10 concave reflector disposed below one of said filaments, said bulb when horizontally placed having a plurality of flutes on the upper portion of

the surface thereof located in vertical planes having a common line of intersection which is tangent to the tip of the bulb and perpendicular to the longitudinal axis thereof, and a plurality of flutes on the lower portion of the surface of said bulb, the flutes on each side of said lower surface being in planes having a common line of intersection which is tangent to the said tip of said bulb and forms an angle with the vertical plane through the bulb axis.
